A method and apparatus for drilling a hole in rock. An open-ended, hardened, drilling head containing a means for creating high-intensity stress waves capable of spalling rock is utilized to drill the hole. A fluid is passed through the drilling head which removes the spalled rock from the drilling head.

METHOD FOR STRESS WAVE DRILLING

This is a division of application Ser. No. 402,547 filed Oct. 1, 1973, now U.S. Pat. No. 3,840,078.

BACKGROUND OF THE INVENTION

1. Field of the invention.

This invention relates, generally, to drilling a hole in rock and, more specifically, to utilizing high intensity stress waves to drill a hole in rock.

2. Description of the Prior Art.

Some prior art drills utilize cavitation drilling techniques. Cavitation is a phenomenon whereby under certain conditions cavities form and violently collapse within a liquid. A shock wave results from the cavitation and may cause considerable mechanical damage to neighboring solid surfaces. Cavitation is induced in a drilling liquid by any suitable technique such as by the generation of acoustic energy. The cavitation threshold is a function of the physical properties of the liquid. The shock wave pressure is a function of the cavitation threshold. Hence, the shock wave pressure is not easily controlled or varied. Liquids having differing physical properties are necessary for creating different shock wave pressures. Since the shock wave pressure necessary to cause spalling of rock varies with the physical properties of the rock, the cavitation method may require different liquids for different rock in order to effect spalling. Also, the range of shock wave pressures achievable by cavitation is limited by the physical properties of the liquid. Thus, certain types of rock are incapable of being spalled by cavitation.

Currently most rock drilling is done by rotary drag bits or percussion bits. In both of these methods a bit made of hardened steel or other hard material scrapes or impacts against the rock until the rock material is disintegrated into a powder. The efficiency of such drills is very low. The rate of drilling and the cost increases greatly for hard formations and deep holes. In addition, the power lost in transmitting power to the rock reaches significant proportions.

The explosive drill, which is currently an operational alternative to rotary-percussion methods, is greatly restricted in application due to the high cost of explosive pellets.

SUMMARY OF THE INVENTION

The general purpose of this invention is to provide a stress wave drill for drilling rock whose shock wave pressure is easily controlled and varied, that does not require different liquids for different rock, whose shock wave pressure is not limited in range, that is highly efficient, and that is more economical to operate than prior art drills. To achieve these significant advantages, one embodiment of the present invention provides an open-ended, hardened, drilling head containing an electrohydraulic pulser. The electrohydraulic pulser creates high-intensity stress waves capable of spalling the rock. These high-intensity stress waves are transmitted to the surface of the rock by a liquid which also serves as a carrier to remove spalled rock from the borehole.

Accordingly, one object of the present invention is to provide an easily controllable stress wave capable of spalling rock.

Another object of the present invention is to provide an easily variable stress wave capable of spalling rock.

Another object of the present invention is to provide

a wide range of stress waves capable of spalling rock.

Another object of the present invention is to provide a highly efficient drill.

Another object of the present invention is to provide 5 a highly economical drill.

Another object of the present invention is to provide a faster drilling rate.

Another object of the present invention is to provide 10 drilling rates that are relatively independent of rock properties.

Another object of the present invention is to increase 15 the percentage of total power of a drill that is transmitted to the rock.

Other objects and more complete appreciation of the 15 present invention and its many attendant advantages will develop as the same becomes better understood by reference to the following detailed description when considered in connection with the accompanying drawings in which like reference numerals designate like 20 parts throughout the figures thereof and wherein

BRIEF DESCRIPTION OF THE DRAWINGS

FIG. 1 is a top view of a specific embodiment of the 25 present invention.

FIG. 2 is a front elevation of the specific embodiment of FIG. 1.

FIG. 3 is a top view of a specific embodiment of the 30 present invention.

FIG. 4 is a front elevation of the specific embodiment 35 of FIG. 3.

DESCRIPTION OF THE PREFERRED EMBODIMENT

Turning to FIGS. 1 and 2, numeral 10 designates a 35

drill stem. Attached to one end of drill stem 10 is an open-ended, hardened, drilling head 12. Hardened drilling head 12 is flared slightly to prevent jamming of drill stem 10 in the borehole 14. Hardened drill head 12 must be capable of withstanding the stress waves 40 generated by electrohydraulic pulser 16 without cracking or breaking.

Electrohydraulic pulser 16 comprises a solid block of 45

electrical insulating material 18. A high voltage electrode 20 extends through insulating material 18 and 50

projects into the space inside drilling head 12. Two ground electrodes 22, located adjacent to high voltage electrode 20, also extend through insulating material 18 and project into the space inside drilling head 12.

Solid block 18 prevents short circuiting of the discharge 55 between electrodes 20 and 22. Electrodes 20 and 22 are enclosed in electrical insulation 24 inside drill stem 10. The description and operation of electrohydraulic pulser 16 is promulgated in detail in Browne,

Allen and Schrom, *Electrohydraulics*, Science Journal, 55 March 1968. Electrode support material 26 supports and protects the electrodes 20 and 22 from impact with spalled rock being carried out of the borehole 14 by fluid 28. Gasket 30 enables electrohydraulic pulser 16 60 to rotate within drill stem 10 and drilling head 12. Gasket 30 forms a fluid-tight seal between electrohydraulic pulser 16 and drill stem 10 and drilling head 12.

Referring to FIGS. 3 and 4, fluid 28 enters drill stem 65 via inlet port 34 and leaves drill stem 10 via outlet port 36. The direction of flow of fluid 28 is indicated by arrows 32. Fluid 28 serves as a carrier for spalled rock. Loose rock spalled by electrohydraulic pulser 16 is carried from the bottom of borehole 14 to outlet port

36, located near the top end of drill stem 10. Thus, the inside diameter of outlet port 36 must be large enough to pass the largest piece of spalled rock that will be produced by electrohydraulic pulser 16. The fluid 28 may be recycled through the drill provided the spalled rock is first removed therefrom. Electrohydraulic pulser 16 in conjunction with gasket 30 divides drill stem 10 in two compartments 38 and 40. Of course, a plurality of compartments of various shapes are possible. The only requirement being that the compartments do not interrupt the fluid flow.

Shock waves from electrohydraulic pulser 16 travel through fluid 28 to the rock face 42. These stress waves load the face 42 which spalls on rebound. Rock particles spalled from the face 42 are removed by fluid 28 15 circulating through drill stem 10 and drilling head 12. The high-intensity stress waves generated by electrohydraulic pulser 16 are typically of microsecond duration. It is noted that electrohydraulic pulser 16 is but one means for generating high-intensity stress waves.

Obviously many modifications and variations of the present invention are possible in light of the above teachings. It is therefore to be understood that within

the scope of the appended claims the invention may be practiced otherwise than as specifically described herein.

We claim:

- 5 1. A method of drilling a bore hole in a rock comprising the steps of:
  - a. moving a bifurcated drill stem downwardly into the bore hole at a controlled rate of movement;
  - b. generating adjacent the bottom of said bore hole stress waves, said stress waves being created by placing a set of three electrodes in said drill stem adjacent to said rock and energizing said electrodes with electrical energy;
  - c. controlling the magnitude and duration of the generated stress waves such that said stress waves spall the rock at the bottom of said bore hole in the vicinity of said electrodes; and
  - d. circulating a flow of drilling liquid downward through one section of said bifurcated drill stem and upwards through the other section of said bifurcated drill stem.
